(57) **CLAIM**

The ornamental design for an antenna, as shown and
described.

DESCRIPTION

FIG. 1 is a perspective view of an antenna showing my new
design in use;

FIG. 2 is another perspective view of the antenna showing my
new design;

FIG. 3 is a front view thereof; and,

FIG. 4 is a side view thereof, the opposite side view being a
mirror image thereof.

The broken lines illustrate environment only and form no part
of the claimed design.
